UNITED STATES PATENT OFFICE.

ELISHA T. BASSETT, OF SPARROWS POINT, MARYLAND.

DESIGN FOR AN AUTOMOBILE-BODY.

56,412.

Specification for Design.

Patented Oct. 26, 1920.

Application filed March 16, 1920. Serial No. 366,430. Term of patent 3½ years.

To all whom it may concern:

Be it known that I, ELISHA T. BASSETT, a citizen of the United States, residing at Sparrows Point, in the county of Baltimore and State of Maryland, have invented a new, original, and ornamental Design for an Automobile-Body, of which the following is a specification, reference being had to the accompanying drawings, forming a part thereof.

The figure is a side elevation showing my new design.

I claim:

The ornamental design for an automobile body, as shown.

ELISHA T. BASSETT.
